E. DAUCHER,
AUTOMATIC FIRE EXTINGUISHER.
APPLICATION FILED APR. 6, 1917.

Patented July 10, 1917.

Inventor
Eugene Daucher
By his Attorney,
Israel Benjamins.

UNITED STATES PATENT OFFICE.

EUGENE DAUCHER, OF WOODSIDE, NEW YORK.

AUTOMATIC FIRE-EXTINGUISHER.

1,232,773.

Specification of Letters Patent. Patented July 10, 1917.

Application filed April 6, 1917. Serial No. 160,282.

To all whom it may concern:

Be it known that I, EUGENE DAUCHER, a citizen of the United States, residing at Woodside, in the county of Queens and 5 State of New York, have invented a new and useful Automatic Fire-Extinguisher, of which the following is a specification.

My present invention is an improvement of the automatic fire extinguisher, for which 10 Letters Patent were granted to me on May 25, 1915, No. 1,140,960, and it consists in the novel features hereinafter described.

The objects of my improvement, in addition to those expressed in my above patent, 15 are:

First, to improve the operation of my automatic fire extinguisher in general.

Second, to prevent the leakage of the extinguishing fluid between the stationary and 20 moving parts of the apparatus.

Third, to spread out the extinguishing fluid over a larger area when in action;—

Fourth, to make the apparatus more simple, durable and inexpensive.

25 I attain these objects by the device illustrated in the accompanying drawings, in which—

Figure 1 is a longitudinal section of my automatic fire extinguisher through the axis 30 of the supply pipe, showing the revolving sleeve 15 in the position when the extinguisher is in action.

Fig. 2 is a top view or plan of my automatic fire extinguisher showing the combustible elements 28 in position when the extinguisher is not in action, but ready for emergencies.

Fig. 3 is a side elevation of my automatic fire extinguisher showing the revolving sleeve 15 in the position when the extinguisher is not in action, and omitting the deflector 20 and yoke 26.

Similar numerals refer to similar parts throughout the several views.

45 10 is the supply pipe for the extinguishing fluid.

11 is a cap for closing the open end of the supply pipe 10, and is secured thereto by means of a suitable thread.

50 13 and 14 are rings or collars, which are stationary with relation to the supply pipe 10, and which may be shrunk on to said pipe or otherwise secured thereto.

15 is a revolving sleeve having a rotary

sliding fit on said pipe 10, and restrained 55 endwise by said cap 11 and collar 14.

Said sleeve 15 is shown as having a circular opening 15^a, which is shown in Fig. 1 as registering with a similar opening 10^a in the supply pipe 10 to permit the escape of 60 the extinguishing fluid when the extinguisher is in action; when not in action, the opening 15^a is in the position shown in Fig. 3, when the supply pipe 10 has its opening 10^a closed by the sleeve 15, which may be 65 made fluid tight either by a snug fit on said supply pipe 10 or by suitable stuffing boxes, if desired.

To keep said sleeve 15 in the normal position, as shown in Fig. 3, I provide the spring 70 22, which is shown in Fig. 2 as connected at one end thereof to said ring 13 and at the other end to the bracket 23, which is shown as secured to said sleeve 15 by means of suitable screws; a similar bracket 24 is 75 secured to said sleeve 15, and a frame 25 attached to the end of said bracket 24; a number of readily combustible elements, such as the strings or cords 28, are fastened each at one end thereof to said frame 25 80 and at the other end to a ring 17, carried by a bar 16 secured to said collar 13; the spring 22 is initially strained and tends to rotate said sleeve 15 out of the position shown in Fig. 3, and into the position shown 85 in Fig. 1; the tension of the strings or cords 28 resists this tendency of the spring 22, until said strings or cords 28 are destroyed by the flame of a conflagration, when said spring is released, and it forthwith turns 90 said sleeve 15 into the position shown in Fig. 1, thereby allowing the extinguishing fluid to escape from the supply pipe 10 through the openings 10^a and 15^a; the deflector 20 then causes the fluid to be spread 95 out over a large area; said deflector 20 is supported in position by the yoke 26, pivot 19 and head 18.

21 are the vanes formed at the rim of said deflector 20, which vanes are adapted 100 to be acted on by the extinguishing fluid, thereby causing said deflector to rotate, and thereby still further spreading said fluid by virtue of the centrifugal force of the rotation of said deflector 20.

27 are the flanges of said yoke 26, shown in Figs. 1 and 2 as secured to said cap 11 and collar 14 by means of suitable screws.

A combustible bag, such as described in my above patent, may be employed to cover the frame 25, cords 28 and the parts of my fire extinguisher adjacent thereto; also a fuse may be employed, as described in said patent.

Instead of the plurality of cords 28 a single long cord may be employed to keep said sleeve in normal position; and by looping said cord around the ceiling or space inclosing the fire extinguisher a number of times before securing the end thereof to the ring 17, a large radius of action may be secured thereby.

Many changes could be made in the details of my automatic fire extinguisher within the scope of my invention; I do not, therefore, restrict myself to the design of the details as shown in the drawings; but I intend to include also all mechanical equivalents and obvious modifications of the same.

What I claim as my invention, and desire to secure by Letters Patent, is:—

1. In an automatic fire extinguisher the combination of a supply pipe for the ex-

tinguishing fluid, a revolving sleeve on said supply pipe, an opening in said pipe and an opening in said sleeve, said opening being adapted to be in registration with each other, a means for keeping said openings out of registration with each other, a means for bringing said openings into registration with each other and a deflector for the extinguishing fluid discharged through said opening.

2. In an automatic fire extinguisher the combination of a supply pipe for the extinguishing fluid, a revolving sleeve on said supply pipe, an opening in said pipe and an opening in said sleeve, said openings being adapted to register with each other, a means for keeping said openings out of registration with each other, a means for bringing said openings into registration with each other, a deflector for the extinguishing fluid discharged from said openings, and vanes on said deflector, said vanes being adapted to cause said deflector to be rotated by said fluid.

EUGENE DAUCHER.
